UNITED STATES PATENT OFFICE.

CHARLES O. SWANGREN, OF MAYWOOD, ILLINOIS.

HAMMER.

Application filed August 17, 1923. Serial No. 657,841.

To all whom it may concern:

Be it known that I, CHARLES O. SWANGREN, a citizen of the United States, residing at Maywood, in the county of Cook and State of Illinois, have invented certain new and useful Improvements in Hammers, of which the following is a specification.

My invention relates to machinists' hammers of the class in which the hammer body is formed of steel or other suitable hard metal, is provided with a striking head of soft metal, such as Babbitt metal, lead, or copper, which may be removed and replaced when battered and worn from use, and a new one substituted. My present invention has for its object the provision of means for facilitating the removal of the worn soft metal member for replacement by a new one. In Patent No. 1,493,055 granted to me on May 6, 1924, I have described and illustrated a hammer of the type mentioned, and my present invention may be considered as an improvement on the tool therein disclosed, by the provision of the novel means for removing the soft metal member, the essential elements of the invention being more particularly pointed out in the appended claims.

In the accompanying drawings forming a part of this specification, and illustrating my invention in a preferred form, Figure 1 is a view of a double-faced hammer, the upper head being shown in a central section and the lower head in elevation; Fig. 2 is a similar view of the same tool, at right angles to the position shown in Fig. 1 and similarly sectioned; Fig. 3 is an end view of the hammer body; Fig. 4 is a perspective of the lifting plug, detached; Fig. 5 exhibits two views of the tool for removing the striking head, in positions 90° apart; and Fig. 6 is a view of a different form of hammer in which my invention may be embodied, having one transversely disposed striking head and one head in longitudinal alignment with the handle.

The same reference characters indicate the same parts in all figures of the drawing.

As shown in the drawing, the hammer body 1, approximately square in cross section and rounded at its edges, is formed with four side faces 2. Transversely of the sides, the body is formed with an obtusely conical face 3 centrally of which is formed an inwardly extending socket for the reception

of a loose plug member 4 of hard metal, such as that of which the body itself is composed, and the soft metal striking body 5. The end faces of the body and inner faces of the cavity together with the outer faces of the plug, form a seat for the reception of the striking head. The plug is formed with a discous head 6 and an axial cylindrical stem 7, which latter extends through an axial reduced inwardly extending portion of the socket nearly but not quite to the inner wall of a transverse cylindrical orifice 8 formed in the hammer body and intersecting the reduced axial portion of the socket which receives the stem of the plug. The faces of the hammer body and plug which form the seat for the soft metal head below the face 3 comprise a cylindrical face 9, an outwardly flaring locking face 10 and an annular transverse face 11 in the hammer body, and an inclined spreading face 12 and obtusely conical face 13 formed in the plug. The face 10 of the hammer body makes a slightly more acute angle with the axis of the socket than the face 12 of the plug.

As in the case of the hammer described in my prior application before referred to, the striking head 5 in its finished form ready for application to the hammer body is formed with an inner annular flange 14 which in the use of the tool is expanded and driven into the socket or seat above described so that when battered and ready for replacement it is seated in and completely fills the socket. To remove it a drift pin 15, having an inclined face 16 is inserted in the cross orifice 8, with its face 16 directed towards the stem 7 of the plug, so that when driven it will wedge the plug outwardly and unseat the striking head. The pin having been withdrawn and the plug detached from the head and replaced in the hammer body, the latter is then ready for the inserting of a new head.

I claim:

1. A hammer having a hard metal body formed with a socket having a reduced axial portion and a transverse orifice intersecting such reduced axial portion, a hard metal plug having a discous outer portion and an inner stem portion extending through said central inner portion of the socket and projecting into said orifice, and a soft metal striking head formed with an annular flange 110

arranged to seat between the discous portion of the plug and the opposite wall of the socket of the hammer body and having its central portion arranged to seat against the 5 discous portion of said plug, said plug being arranged to cooperate with a wedge in said orifice to unseat the striking head.

2. A hammer having a hard metal body formed with a socket having adjacent its 10 bottom an undercut locking face and also formed with an orifice communicating with the central inner portion of said socket, a hard metal plug arranged centrally within said socket adjacent the locking face of such 15 socket, and a soft metal striking head seated in said socket and seating against said plug, said plug being provided on its outer side with inclined spreading faces adapted to spread said striking head into locking en- 20 gagement with said locking face of the

socket and also being exposed to a drift pin through said orifice.

3. A hammer having a hard metal body formed with a socket having adjacent its 25 bottom an undercut locking face and a reduced axial portion, and also formed with a transverse orifice communicating with the bottom of said reduced axial portion of the socket, a hard metal plug having a discous outer portion formed with a peripheral 30 spreading face and an inner stem portion extending through said reduced axial portion of the socket and into said transverse orifice, and a soft metal striking head seated in said socket and seating against said plug, 35 the stem of said plug being arranged to cooperate with a wedge-faced drift pin inserted through said orifice.

CHARLES O. SWANGREN.
